COLLOID MILL

Louie H. Morehouse, Los Angeles, Calif., assignor
to Glenn H. Morehouse, Los Angeles, Calif.

Application August 15, 1939, Serial No. 290,231

2 Claims. (Cl. 83—13)

This invention relates to improvement in colloid mills for reducing solids suspended in liquids to finely divided form, as for example, the pigments of paints and the like or for the grinding of matter to form pastes and emulsions, as in the manufacture of mustard, etc.

An object of the invention is to provide in a colloid mill such as described an improved mounting for the rotor and stator grinders, by means of which said grinders may be quickly and easily removed and replaced.

Another object of this invention is to provide in a colloid mill such as described, an improved drive shaft mounting and adjusting means for the rotor grinder of the mill, whereby the number of parts usually required is reduced, the structure is more rugged, adjustments are more readily effected, and a more accurate milling operation is made possible with a minimum of wear and parts replacement.

A further object is to provide in a mill such as described an improved liquid sealing means for protecting the main bearing from damage by fumes and vapors arising in the mill during treating of certain materials.

Another object is to provide a colloid mill which will be superior to such mills as heretofore used by reason of the particular construction and relative arrangement and combination of the parts and elements thereof, and to the end that the fewer parts are used, a greater variety of milling operations may be carried out, and a greater nicety of adjustment and operation of the mill is afforded.

With the foregoing objects in view, together with such other objects and advantages as may subsequently appear, the invention is carried into effect as illustrated by way of example in the accompanying drawing, in which:

Fig. 1 is a vertical sectional view of a mill embodying my improvements;

Fig. 2 is a top plan view of the mill, on a reduced scale compared to Fig. 1;

Fig. 3 is a cross sectional view taken on line 3—3 of Fig. 1;

Fig. 4 is a perspective view of the feeding member for effecting and control the feed to the mill;

Fig. 5 is an enlarged fragmentary vertical section of the liquid seal for protecting the main bearing of the mill;

Fig. 6 is a fragmentary vertical section showing the manner of mounting and removing the stator grinder, and illustrating such grinder as when removed from its seat.

One form of colloid mill embodying my inven-

tion includes, as shown in the accompanying drawing, a hollow or generally tubular pedestal A suitably water jacketed and provided at its upper end with a head B removably bolted thereto and forming therewith a grinding chamber C, contiguous with which is a spillway D likewise formed as a part of the pedestal.

Matter to be ground or treated is fed through an intake opening E in the head B, to the rotor and stator grinders R and S in the grinding chamber, and such matter upon being ground will pass between said grinders into the spillway and be discharged over the inclined bottom wall F thereof.

The stator grinder S is annular and detachably held against an annular seat 7 on the head B by means of a retaining ring 8 secured by screws 9 to the head. This retaining ring surrounds the stator grinder and abuts the seat 7 while its outer periphery is engaged with the annular wall 10 of the head. The wall 10 is relieved as at 10' to permit of ready removal of the ring 8. A shoulder 11 on the inner periphery of the ring seats against an annular shoulder 12 on the grinder whereby to retain the latter against its seat. By reason of this construction the stator grinder will not stick to the head or otherwise prove difficult of removal when replacement, as is often necessary, is required. When the screws 9 are withdrawn the grinder S and ring 8 are readily removable as a unit as shown in Fig. 6 and this is a noteworthy improvement in this art.

Referring now to the rotor grinder R as best shown in Figs. 1 and 3, such grinder is in the form of circular disk having an annular beveled grinding face 13 arranged to coact with the beveled face 14 on the stator grinder S. A plate 15 supports the grinder R and is keyed as at 16 on a rotary shaft 17 extending upwardly in the pedestal as is customary in mills of this type, said shaft being driven by any suitable means, not shown. An annular band 18 surrounds the plate 15 and forms therewith a socket in which the rotor grinder R is fitted as shown in Figs. 1 and 5. This band has an inwardly extending annular flange 19 located intermediate its upper and lower edges and secured against the under side of the plate 15 by means of screws 20 as shown in Fig. 5. The shaft 17 extends through the grinder R and has a nut 21 threaded on its upper end for forcing an annular clamp plate or washer 22 against said grinder whereby to secure such grinder for rotation with said shaft. It is now seen that the grinder R may be quickly and easily removed from the shaft and fixed thereto as aforesaid by

reason of the construction and arrangement of the nut 21, washer 22, band 18 and screws 20.

The shaft 17 comprises an upper vertically adjustable section 17a and a lower section 17b splined by means of a sleeve 23 and the usual keyway 24, and key 25 as shown in Fig. 1. This affords vertical adjustment of the shaft section 17a to reset the rotor grinder R to compensate for wear or to change the relationship of the grinders to suit the particular material to be treated in the mill.

A tubular shell 26 is formed integrally with the spillway bottom wall F and extends above and below said wall, the lower end thereof having an internal annular and screw threaded flange 27. A sleeve 28 is mounted in the shell 26 so as to extend above and below said shell and its lower end is externally threaded as at 29 for cooperation with the threads of the flange 27 whereby the sleeve 28 is vertically adjustably supported in and by said shell. The upper end of the sleeve 28 is counterbored to receive a ball bearing 30 for the shaft 17. As the lower end of the sleeve 28 extends below the shell 26 and access thereto may be had through a hand hole 31 in the stand or pedestal A, said end is provided with openings 32 whereby the sleeve may be rotated and thereby vertically adjusted with a suitable spanner, not shown, and then locked in adjusted position by means of the lock nut 33. The upper section 17a of the shaft, the bearing and rotor grinder R move with the sleeve 28 when the latter is vertically adjusted, for the purposes aforementioned. It should be noted that the shell 26 is formed with a small internal flange 34 at its upper end which engages and centers the sleeve 28, said sleeve being otherwise circumferentially spaced from said shell except where threaded thereto at its lower end.

It is now seen that the shaft 17 and rotor grinder R are supported for vertical adjustment by a simple and rugged mounting consisting of the shell 26 and sleeve 28 and comprising fewer parts than heretofore used in the art.

As a means for protecting the bearing 30 from damage by fumes and vapors arising from the material being treated in the mill, an especially constructed oil seal is provided. This sealing means includes, as best shown in Fig. 5, an annular well 36, suspended by an annular flange 37 therefrom within the counterbore at the upper end of the sleeve 28, said well being circumferentially spaced from the shaft and supported on top of the bearing 30. The well 36 is filled with oil and a sealing cylinder 38 carried by the plate 15 extends into said well whereby to form an effective seal. This cylinder is provided with a flange 38' secured by screws 39 to the plate 15. The skirt of the bank 18 extends below the upper end of well 36 and acts as a baffle or guard to prevent solids and liquids from being thrown or deposited in the well.

As a means for controlling the feed of matter to the mill and for effecting a positive feed of such matter between the grinders, I provide a bladed circular feed disk 40 which is clamped on the upper end of the shaft 17 by the nut 21 so as to rotate with said shaft. The blades 41 of this disk are bent as in a fan to feed the matter between the grinders as will be apparent in Fig. 1; said disk being positioned adjacent and substantially equal in area to the inner end of the intake opening leading into the grinding chamber. Due to its size and position the disk 40 will regulate the feed of matter to the grinders as well as

force such matter into contact with the grinders.

As a means for facilitating feed of matter between the grinders the stator grinder S is arranged with the upper portion of the beveled face 14 of its inner periphery extended above the face of the central portion of the rotor grinder R to such extent as to surround the outer margin of the feed disk 40; the upper margin of the face 14 being positioned in close proximity to the tips of the blades 41 of the disk with the beveled face leading outwardly and downwardly away from the disk and overlying the beveled face 13 of the grinder R and abutting the face 13 intermediate the margins thereof. To further enhance the action of the feed disk 40 the upper marginal portion of the face 13 is inclined away from the contiguous portion of the face 14 to form a channel 13a of V-shaped cross section converging downwardly from the tips of the blades 41 on the feed disk to a narrow line of contiguous surfaces of the grinders S and R.

It will now be apparent that a colloid mill constructed and arranged as hereinbefore described and as shown in the accompanying drawing, will provide for the advantages, purposes and objects herein stated in a particularly efficacious manner, due to the simplicity of construction and arrangement of the parts and elements thereof, the use of comparatively few parts and the mounting and adjusting means for the grinders as well as the bearing and the liquid seal protection means for the bearing.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In a colloid mill, a pedestal having a grinding chamber provided with an intake opening, an annular stator grinder mounted on said chamber and surrounding the inner end of said opening, a rotor grinder in said chamber for cooperating with said stator grinder, a feed disc fixed for rotation with said rotor grinder upon the upper face thereof and having peripheral blades formed by radially slitting the disc inward from the periphery at circumferentially spaced points and bending the slit peripheral blades relative to the plane of the disc to feed matter from said opening to said grinders, said disc being disposed in the opening or bore of said annular grinder and above the coacting grinding portions of said grinders.

2. In a colloid mill, a rotary grinder having a beveled outer peripheral face, and an annular stator grinder having a beveled inner peripheral face arranged with the upper marginal portion of said inner face protruding above the upper margin of the beveled outer face of the rotary grinder and with its lower margin overlying only an intermediate portion of said beveled outer face; said beveled outer face being inclined at its upper portion inwardly away from the intermediate and upper portion of the beveled inner face of said stator grinder, a flat feed disc mounted on said rotary grinder and having blades arranged radially and circumferentially about the periphery of the disc with their flat portions positioned in the direction of rotation but arranged at a slight inclination relative to the plane of the disc.

LOUIE H. MOREHOUSE.
